DESIGN FOR A CIGARETTE HOLDER

Mabel F. Zelinski, Seattle, Wash.

Application June 28, 1943, Serial No. 110,545

Term of patent 14 years

To all whom it may concern:

Be it known that I, Mabel F. Zelinski, a citizen of the United States, residing at Route 7, Box 520G, Seattle, in the county of King and State of Washington, have invented a new, original, and ornamental Design for Cigarette Holders, of which the following is a specification, reference being had to the accompanying drawing, forming part thereof.

Fig. 1 is a bottom plan view of a cigarette holder showing my new design;

Fig. 2 is a side elevational view thereof;

Fig. 3 is a top plan view thereof; and

Fig. 4 is a perspective view thereof.

I claim:

The ornamental design for a cigarette holder, as shown.

MABEL F. ZELINSKI.
